UNITED STATES PATENT OFFICE.

FRANK A. RYDER, OF CHICAGO, ILLINOIS.

ENVELOPE.

Application filed November 13, 1922. Serial No. 600,569.

To all whom it may concern:

Be it known that I, FRANK A. RYDER, a citizen of the United States, and a resident of the city of Chicago, county of Cook, and 5 State of Illinois, have invented certain new and useful Improvements in Envelopes, of which the following is a specification.

My invention relates to envelopes, and more particularly to the type of envelope 10 with an openable portion or flap for inspection of the contents by the postal authorities.

A primary object of my invention is to provide an envelope of the type referred to 15 having means for securely interlocking and retaining the inspection flap in position on the envelope, to prevent accidental escape of the contents, during filling and transit.

Other objects will appear hereinafter. 20 The invention consists in the combinations and arrangements of parts hereinafter described and claimed.

The invention will be best understood by reference to the accompanying drawings 25 forming a part of this specification, and in which,

Fig. 1, is a view of the blank from which one form of envelope embodying my invention may be constructed;

Fig. 2, is a view showing the envelope completed, with the sealing flap open;

Fig. 3, is a view showing the sealing flap in closed position, but the removable end or inspection flap withdrawn;

Fig. 4, is an enlarged vertical sectional view taken on line 4—4 of Fig. 2;

Fig. 5, shows a modified form of blank from which the envelope may be constructed;

Fig. 6, is a view showing the modified form of envelope completed, with the sealing flap open;

Fig. 7, is a view showing the sealing flap in closed position but the openable portion 45 or inspection flap withdrawn, and

Fig. 8, is an enlarged vertical sectional view taken on line 8—8 of Fig. 6.

The form of my invention illustrated in 50 Figs. 1 to 4 comprises a face member or front portion 6 and a back portion or flap 7 folded up from the lower edge of said front portion, an end portion or flap 8 being folded between portions 6 and 7 and fastened in position by adhesive means 9 provided on the back portion, or with any suitable fastening means. A second end portion or in-

spection flap 10 is folded between the portions 6 and 7 and is provided with a lip 11 at its upper end which is folded over the back portion 7 and has means 12, such as a few drops of adhesive material, or any other suitable means, which fastens the lip 11 down on said end portion 10, said fastening means engaging in a notch or flaring slot 13 provided in the upper edge of said back portion and bearing behind a tongue 14 on said back portion to retain the end portion securely in position, during filling of the envelope, and releasably for inspection. A sealing flap 15 with adhesive means 16 is 70 provided to close the envelope.

The modified form of envelope shown in Figs. 5 to 8 is similar to the preceding form, and comprises the front and back portions 6' and 7', an end portion 8' fastened to the back portion by adhesive means 9' also the openable end portion or inspection flap 10' provided with lip 11' folded over the back portion and fastened thereover with fastening means 12' which fixes the folded lip 11' down onto the end portion, said means 11' and 12' engaging in notch or flaring slot 13' back of the tongue 14'. In this form the openable end portion or inspection flap extends to the middle of the envelope, and the cooperating lip, the fastening means, and the notch and tongue are therefore positioned near the upper middle portion of this envelope instead of being located adjacent the upper end near the openable end portion, as in the preceding form.

The envelope is put on the market with the openable end portion 10 placed in position between the front and back portions and the lip 11 fastened down over the back portion, with the fastening means 12 engaging behind the tongue 14; and when the user of the envelope fills the same it is found that the interlocking means 11, 12, 13, and 14, provides a very secure means for firmly retaining the end flap 10 in closed position during filling and during subsequent transmission, thereby preventing the unpleasant accidental discharge often occurring with the usual inspection envelope, both during filling and during transit. When it is desired to withdraw the enclosed matter it is merely necessary to place the fingers in between the inspection flap 10 and the back portion 7 thereby moving down the unsealed upper corner of the back portion 7 with its tongue 14 which is thereby disengaged from 100 105 110

the fastening means 12, thus permitting the withdrawing of the inspection flap 10 and the removal of the enclosed matter.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. An envelope provided with a front and having a back portion and an end portion extending from said front, a notch cut in the edge of one of said portions to provide a holding tongue, and a lip on the other of said portions overlapping said tongue and having means for fastening it down and for engaging in said notch behind said tongue to hold said end in position during filling but to permit ready withdrawal of said end for inspection.

2. An envelope having front and back portions, a notch cut in said back portion forming a tongue, and an end portion folded between said front and back portions and having an extension overlapping said back portion, said extension and end portion being provided with means engaging in said notch against said tongue for releasably retaining said end portion in position.

3. An envelope having front and back

portions, a sealing flap on said front portion, fastening means on said flap for fastening it to said back portion, said fastening means being removed a distance from one end to permit bending the adjacent part of said back portion, an end portion at said end provided with a folded extension held down by interlocking means, and tongue means at the upper edge of said back portion for engaging behind said interlocking means to hold said end portion during filling and being releasable therefrom by an outward movement of said back portion to permit withdrawing said end portion.

4. An envelope having front and back portions and end portions folded therebetween, means for fixing one end portion to the back portion, a sealing flap for fastening over said back portion, a lip on the other end portion foldable over said back portion, a slot and tongue on the upper edge of said back portion, and adhesive means for fastening the folded lip on said end portion, said adhesive means being positioned within said slot and with the surrounding part of said lip engaging behind said tongue for securely holding said end portion in position during filling and permitting convenient release thereof for inspection.

In testimony whereof I have signed my name to this specification in the presence of two subscribing witnesses.

FRANK A. RYDER.
